(57) **CLAIM**

The ornamental design for a spectroscopy device, as shown and described.

DESCRIPTION

FIG. 1 is a front isometric view of a new design for a spectroscopy device;

FIG. 2 is a rear isometric view of the spectroscopy device of FIG. 1;

FIG. 3 is a left side view of the spectroscopy device of FIG. 1;

FIG. 4 is a right side view of the spectroscopy device of FIG. 1;

FIG. 5 is a top plan view of the spectroscopy device of FIG. 1;

FIG. 6 is a bottom plan view of the spectroscopy device of FIG. 1;

FIG. 7 is a front view of the spectroscopy device of FIG. 1;

FIG. 8 is a rear view of the spectroscopy device of FIG. 1;

and,

FIG. 9 is a front isometric view of the spectroscopy device of FIG. 1.

The broken lines in the drawing views are included for the purpose of illustrating portions of the spectroscopy device that form no part of the claimed design.
